US0D1088516S

(12) **United States Design Patent** (10) **Patent No.:** **US D1,088,516 S**
(45) **Date of Patent:** **** Aug. 19, 2025**

(54) **WALLET**

- (71) Applicant: **CTB HOLDINGS LLC**, Portola Valley, CA (US)
- (72) Inventors: **Thuan Tran**, San Jose, CA (US); **Charlie Carroll**, Palo Alto, CA (US); **Binh Tran**, Santa Clara, CA (US)
- (73) Assignee: **CTB HOLDINGS LLC**, Portola Valley, CA (US)

(**) Term: **15 Years**

(21) Appl. No.: **29/877,805**

(22) Filed: **Jun. 12, 2023**

Related U.S. Application Data

(63) Continuation-in-part of application No. 18/078,881, filed on Dec. 9, 2022, now Pat. No. 11,737,531, and a continuation-in-part of application No. 17/887,350, filed on Aug. 12, 2022, now Pat. No. 11,786,018.

(57) **CLAIM**

The ornamental design for a wallet as shown and described.

DESCRIPTION

FIG. 1 is a front and first side perspective view of a wallet in a closed configuration;

FIG. 2 is a back and second side perspective view thereof;

FIG. 3 is a front view thereof;

FIG. 4 is a back view thereof;

FIG. 5 is a first side view thereof;

FIG. 6 is a second side view thereof;

FIG. 7 is a top view thereof;

FIG. 8 is a bottom view thereof;

FIG. 9 is an interior perspective view of the wallet in an open configuration; and,

FIG. 10 is an exterior perspective view thereof.

The broken lines in the drawings depict portions of the wallet that form no part of the claimed design.
